UNITED STATES PATENT OFFICE.

WILLIAM F. LAUTENSCHLAGER, OF CINCINNATI, OHIO, ASSIGNOR OF ONE-HALF TO THE KIPPENDORF-DITTMANN COMPANY, OF CINCINNATI, OHIO, A CORPORATION.

CEMENTING-MACHINE.

No. 810,873.

Specification of Letters Patent.

Patented Jan. 16, 1906.

Application filed April 26, 1905. Serial No. 257,466.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Cementing-Machines, of which the following is a specification.

My invention relates to a cementing-machine.

One of the objects of the invention is to provide a cement receiving and distributing roll having its periphery formed of a glazed surface.

Another object of my invention relates to the driving mechanism for rotating the cementing-roll.

Another object of my invention is to provide detachable cement-reservoir and roll-scaper, whereby the parts can be readily removed for cleaning, and, further, enabling the cement-reservoir through its detachable means of having a pivotal movement toward the cement-distributing roll, thereby assuring a uniform feeding action of cement upon the periphery of the roll when the valve of the reservoir is opened.

Another object of my invention is to provide a valve and adjusting mechanism for the cement-reservoir, whereby the opening can be delicately regulated, so as to insure the proper delivery of cement, which varies in consistency, so as to insure under all conditions a proper delivery and spreading of the cement.

Other features of the invention are more fully set forth in the description of the accompanying drawings, forming a part of this specification, in which—

Figure 1 is a central vertical section of my apparatus, partly in elevation. Fig. 2 is an end elevation of the same with the standard or base omitted. Fig. 3 is a perspective view of the wiper of the cement-distributing roll.

Fig. 4 is a front elevation of the cement-reservoir. Fig. 5 is an enlarged section on line *x x*, Fig. 2. Fig. 6 is an enlarged section on line *w w*, Fig. 4.

A represents the base of the frame provided with an upwardly-extending standard or support *A'*, to which is secured a yoke-shaped bracket or support *B*, upon which the various parts are journaled and support-

ed. 1 represents a shaft journaled in bearings formed integral with the bracket *B*. 55 Upon this shaft 1 is fixed a cement receiving and distributing roll 2. This roll is driven in a direction toward the wiper 28, Fig. 2, by the following mechanism: 3 represents a gear upon shaft 1 and pinned to the hub of 60 the roll 2 and in mesh with a pinion 4, cut upon the stud-shaft 5, journaled in an eccentric bushing 6, said eccentric bushing being supported in a bearing formed integral with the bracket *B*. This eccentric is provided 65 for a convenient machining, rendering it possible to adjust the pinion in proper driving engagement with the gear-wheel. This shaft 5 projects outwardly, the free end being provided with a loose pulley 7 and a tight pulley 8. Thus as motion is imparted to the tight pulley 8 it will revolve shaft 5, pinion 4, gear 3, and roll 2. It will be seen that this construction of standard and driving mechanism renders possible the construction 70 of a neat, durable, and compact machine 75 with the driving-gears within the rim of the roll 2, the tight and loose pulleys being the only members of the driving mechanism that are exposed.

I have found by experience that it is necessary in the perfect operation of the machine to coat the periphery of the roll 2 with a material presenting a hard glazed surface, for it has been found that when fibrous material, 85 such as linings of a shoe, are presented to the surface of the roll for applying cement thereto—that is, to the lining—a small amount of lint is deposited upon the roll. This is readily removed from the hardened surface by a suitable wiper, to be hereinafter described. It has been found that when a surface other than a glazed surface—as, for instance, say, a rubber belt or the like—is secured to the periphery of the roll such lint will adhere to the 90 roll and cannot be taken up by the wiper, owing to the flexibility of such roll, and will pass under the wiper and in the course of a short time by an extended use of the machine will greatly vary the plane of the surface of the roll, thereby causing an irregular feed or deposit of cement upon the roll and also cause the same to receive a surplus of cement at various surface positions, which surplus cement frequently coagulates and 95 drops to the floor, causing a loss of cement,

making it difficult to keep the machine clean, and, in fact, rendering the machine useless. By coating the roll with a glazed surface I overcome this serious objection and, in fact, 5 am enabled to maintain a clean machine and roll having a deposit of glue upon the surface only of the required and desired thickness. 9 represents such material, which is preferably composed of a coating of hard rubber 10 having a glazed finish.

10 11 represent arms fixed to the bracket B, the free ends of which are provided with a rod 12, journaling in said arms and upon which rod the cement-reservoir 13 is pivotally supported by means of ears 14.

15 represents the base portion of the reservoir having an inclined face portion 16, adapted to bear against the periphery or surface of the roll 2. This surface is provided with the 20 channel 17, extending the entire width of the reservoir, forming a cement-receiving port for such surplus cement as may possibly escape from the wiper 28. 18 represents distributing-channels leading from the channel 17 to 25 the mouth of the valve 19, whereby the surplus cement thus caught up will be commingled with the fresh supply deposited upon the surface of the roll when the valve is opened.

30 The construction of the valve is as follows: 19 represents a valve of tubular form, having a cut-away portion 20, whereby an abrupt shoulder 21 is formed, said shoulder being adapted to engage against a shoulder 22, 35 formed on the base portion of the reservoir, whereby when the parts are brought into engagement with each other they will be securely locked and form a very effective seal. The valve is seated in the base portion of the 40 reservoir and held in position by the following instrumentalities: 23 represents valve-seats for the cylindrical valve 19. (See Fig. 5.) 24 represents a boss formed on the base portion of the reservoir and extending the entire length thereof. 25 represents a plate secured to said boss by means of screws, said plate performing the office of holding the valve securely in position. The free end of said plate has an inward spring-like tension, 45 whereby the valve will always be held against its bearing parts, preventing any leaking at such points. 26 represents a packing inserted between the valve and boss and held in position by the plate 25, thereby preventing 50 any leakage at such point and also forming an abutment for the valve. 27 represents a lever fixed to the valve at one end, by means of which the valve-opening is controlled. By this construction of valve it will be seen that 55 the parts are readily removable, enabling the same to be easily cleaned, as the class of cement used is very difficult to handle and when it becomes dry from non-use renders the device almost entirely impractical, requiring the same to be cleaned, which is a

very difficult operation, as the parts in many instances are required to be sandpapered before they can be brought or placed back into their operating positions. With my construction of valve I overcome these objections, as it is impossible for the cement to permeate into the valve-seats. By making the cylindrical well below the outlet at 21 a body of cement is maintained below the discharge-point, which prevents the hardening of cement at the point of discharge, insures a free flow thereof, and is the preferred form of construction. It will also be noticed that the position which the valve and reservoir assume with relation to the roll is such that the 75 valve is opened to a greater breadth than the thickness of cement applied upon the roll. This I regard as a very important feature in obtaining a uniform spreading of cement upon the roll-surface and which I have found by 80 experience can only be accomplished by a free supply, and with my construction I produce such results without causing a surplus of cement to be supplied to the roll.

28 represents a wiper provided with depending ears 29, adapted to be detachably supported upon the rod 12. This wiper is provided with a knife-edge 30, bearing against the surface of the roll 2, the rearward portion of the wiper draining into the reservoir 13. This reservoir may be provided with a screen at such draining-point to catch up any residue. The wiper may have a flexible head instead of the knife-edge.

Having described my invention, I claim— 100

1. A cementing - machine comprising a frame, a hollow spreading - roll journaled thereon, a driving-shaft journaled on said frame and extending into said hollow roll, means for rotating said roll, a cement-reservoir 105 pivotally supported on said frame, having a distributing portion bearing against the surface of the roll, and a hollow cylindrical valve seated within said reservoir, and means for rotating said valve to adjust the delivery 110 of cement, substantially as described.

2. A cementing - machine comprising a frame, a cement - supplying roll journaled upon said frame, driving mechanism comprising a stud-shaft, provided with a fixed 115 pulley and pinion supported at opposite ends, a shaft to which said cement-roll is fixed and journaled, a gear mounted on said shaft and fixed to said cement-roll and receiving motion from said pinion, said gear and pinion 120 being mounted within the rim of the cement-roll, a cement-reservoir pivotally supported on said frame and detachable therefrom, its distributing portion being held by gravity against the surface of the roll, a valve seated 125 within said reservoir, and a wiper detachably supported on the frame, having a bearing upon the periphery of the roll and projecting into the reservoir, substantially as described.

3. A cementing - machine comprising a 130

frame, a cement - supplying roll journaled upon said frame, being provided with a glazed surface, means for driving said roll, a cement-reservoir detachably supported on said frame, provided with a roll-bearing surface held by gravity against the roll, a valve seated within said reservoir at such roll-bearing portion of the reservoir, and adapted to form a seal therewith and with the parts so arranged that the valve-opening is greater than the thickness of the cement applied to the surface of the roll, and a wiper detachably supported on the frame, having a bearing upon the periphery of the roll and projecting into the reservoir, substantially as described.

4. A cementing - machine comprising a frame, a cement - supplying roll journaled upon said frame, means for driving said roll, a cement-reservoir detachably supported on said frame, and provided with a roll-bearing surface held by gravity against the roll, a valve seated within said reservoir at such roll-bearing portion of the reservoir, and adapted to form a seal therewith and with the parts so arranged that the valve-opening is greater than the thickness of the cement applied to the surface of the roll, and a wiper detachably supported on the frame, having a bearing upon the periphery of the roll and projecting into the reservoir, substantially as described.

5. A cementing - machine comprising a frame, a cement - supplying roll journaled upon said frame, means for driving said

roll, a cement-reservoir detachably supported on said frame, provided with a roll-bearing surface held by gravity against said roll, said bearing-surface being provided with surplus cement receiving and distributing channels leading to the mouth of the valve, a valve seated within said reservoir at such roll - bearing portion of the reservoir, and adapted to form a seal therewith and with the parts so arranged that the valve-opening is greater than the thickness of the cement applied to the surface of the roll, and a wiper detachably supported on the frame, having a bearing upon the periphery of the roll and projecting into the reservoir, substantially as described.

6. In a cementing-machine, a cementing-roll provided with a glazed surface, a reservoir having an outlet-valve engaging against the roll and adapted to supply a coating of cement, and a wiper engaging said roll, substantially as described.

7. In a cementing-machine, a cementing-roll having a glazed surface, a reservoir provided with a cylindrical valve-outlet bearing against said roll, means for regulating said valve, and a wiper engaging said roll, substantially as described.

In testimony whereof I have hereunto set my hand.

WILLIAM F. LAUTENSCHLAGER.
